J. PERRY,
SAFETY APPLIANCE FOR FLUID CONDUITS,
APPLICATION FILED OCT. 10, 1918.

1,296,213.

Patented Mar. 4, 1919.

FIG. 2.

FIG. 1.

Inventor:

*James Perry,
By his attorney,
Charles S. Gooding.*

UNITED STATES PATENT OFFICE.

JAMES PERRY, OF SOMERVILLE, MASSACHUSETTS.

SAFETY APPLIANCE FOR FLUID-CONDUITS.

1,296,213.

Specification of Letters Patent.

Patented Mar. 4, 1919.

Application filed October 10, 1918. Serial No. 257,543.

To all whom it may concern:

Be it known that I, JAMES PERRY, a citizen of the United States, residing at Somerville, in the county of Middlesex and State of Massachusetts, have invented new and useful Improvements in Safety Appliances for Fluid-Conduits, of which the following is a specification.

This invention relates to improvements in safety appliances for fluid conduits and more particularly for gas conduits. The object of the invention is to provide a simple inexpensive device adapted to automatically shut off the supply of fluid when any material fluctuation in the pressure of said fluid takes place. Another object of the invention is to provide means for utilizing the pressure of fluid to reopen the conduit for the passage of the fluid therethrough.

20 The invention consists in the combination and arrangement of parts set forth in the following specification and particularly pointed out in the claims.

Referring to the drawings:

25 Figure 1 is a plan view of an appliance embodying my invention illustrating the top of the casing thereof removed and a portion of said casing shown in section.

Fig. 2 is a vertical section partly in elevation taken on the line 2—2 of Fig. 1.

Like numerals refer to like parts in both views of the drawings.

In the drawings, 1 represents a casing of any suitable shape or construction having a discharge tube 2 connected therewith preferably at one end. A valve 3 is connected with said tube 2 preferably upon the interior of said casing and is adapted to control the discharge of fluid from said casing through said discharge tube. Numerous types of valves may be employed in this connection but for convenience a valve is shown having a passage 4 extending therethrough and connecting with the interior of the discharge tube 2.

45 A tapered plug 5 is arranged to seat in a correspondingly tapered recess 6, said plug being movable relatively to said seat to open or close the passage 4 of said valve.

A lever 7 is pivoted within said casing, in the present instance by means of center screws 8 and 9 secured to the side walls of said casing and engaging opposite ends of a shaft 10 constituting a portion of said lever. This lever is operatively connected at one

end 11 with said plug 5 and its pivotal movements cause said valve plug 5 to be moved from one of its positions to the other.

The free end portion 12 of said lever 7, which is the operating end thereof, is longer than the portion which engages said plug 5 for the purpose of multiplying, by increased leverage, the power exerted against said free end to rock said lever. Attached to the free end of said lever is a pocket-like member 13 consisting of a substantially horizontal portion 14 and a substantially vertical portion 15 connected together and extending transversely of said casing.

The normal position of the lever 7 will be as illustrated by its full line position Fig. 2. The weight of said valve plug upon said lever being sufficient to maintain said lever in this position and when in such a position the valve 3 will be closed, preventing any discharge of fluid from the casing. The casing 1 is also provided with a fluid supply tube 16 preferably connected with said casing at the end thereof, opposite the discharge tube 2.

The supply tube 16 protrudes into said casing and has at its inner end a nozzle preferably consisting of a cap 17 provided with a discharge orifice 18 directed downwardly, and at an angle to the bottom of said casing. This nozzle is adapted to discharge a jet of fluid into said casing 1 beneath the end of the lever 7 bearing said pocket-like member 13 and has no effect upon said lever when the same is in its full line position.

The supply tube 16 has a shut-off valve 19 connected therewith outside of the casing 1 by means of which the supply of fluid to the casing may be shut off. The lever 7 and valve plug 5 will remain in their closed positions until some additional agency is employed to rock said lever about its axis from the full line position thereof to the position shown in the dotted lines in said Fig. 2. When such a movement of said lever takes place the valve 3 will be opened and the fluid or gas contained within the casing 1 will escape from said valve to said tube 2.

When said lever 7 is moved to its open position, which is the other extreme position of said lever, the pocket-like member 13 will come to rest directly in the path of the jet of fluid discharging through the discharge orifice 18 of said nozzle, said jet being di-

rected into the angle formed by the portions 14 and 15 and the direction of the force of said jet being below the axis of said lever, the tendency thereof will be to maintain said lever in its dotted line position just as long as the force of said jet is sufficient to overcome the opposing action of the valve plug 5 the weight of which constantly tends to return said lever to its normal position.

10 Should the pressure or force of the jet fluctuate sufficiently to allow the weight of the plug 5 to overcome the pressure of said jet upon said lever said lever will return to its normal position and there remain until 15 the same is again depressed. Numerous devices may be employed for depressing said lever 7. The preferred means however, consists of an auxiliary tube 20 connected with the main supply tube 16 in advance of the 20 valve 19 as shown at 21. The tube 20 also has a shut-off valve 22 arranged therein outside of the casing 1. Beyond the valve 22, said tube passes through the wall of said casing to the interior thereof where it is 25 provided with a nozzle preferably consisting of a cap 23 secured over its inner end and having a discharge orifice 24 adapted to direct a jet of fluid into the angle of the pocket formed by the members 14 and 15 when said 30 lever is in its uppermost or full line position.

A cap 25 is attached to the top of the casing 1 preferably by screws 26 thus providing access to the interior of the casing to adjust or repair the operating parts of 35 the device. The operation of the appliance hereinbefore specifically described is as follows:

Assuming the lever to be in its normal position, as shown in full lines Fig. 2, and 40 the valve closed, also the valves 19 and 22 closed, the valve 22 is first opened permitting fluid to pass from the supply tube through the tube 22 into the casing 1 discharging into said casing through the discharge orifice 24. When the force of the 45 jet of fluid, discharged through said orifice, has become strong enough to rock the lever 7 from the full line position to the dotted line position of Fig. 2 the plug 5 will be 50 lifted and said valve opened permitting gas or fluid to discharge into the discharge tube 2.

After said lever has been moved to said dotted line position the valve 19 must be 55 opened and a jet of fluid discharged through the orifice 18 against the end of said lever which will maintain said lever in its depressed position as long as the pressure of said jet remains strong enough to overcome 60 the weight of the plug 5 which it will do under ordinary conditions. Any material fluctuation, however, in the pressure of fluid from said supply tube will allow said lever 7 to be moved back from its normal position by the weight of said plug and conse-

quently the discharge of fluid from the casing will be cut off by the closing of the valve.

As soon as the pressure of fluid from the discharge orifice has become strong enough 70 to maintain said lever in its depressed position the valve 22 should be closed so that the said lever 7 will be acted upon solely by the jet from the orifice 18. In order to insure the automatic closing of the valve 75 22 after the valve 19 has been opened said valve is provided with a spring 27 connected at one end with the operating lever 28 of said valve, the opposite end being attached to a portion of said casing. A stop pin 29 prevents the spring 27 from moving said valve beyond its fully closed position.

Having thus specifically described my invention what I claim and desire by Letters Patent to secure is:

1. A device of the class described having in combination, a fluid tube, a valve adapted to control the passage of fluid through said tube, a lever operatively connected at one end with said valve and having at its opposite end a pocket the weight of said valve being normally adapted to maintain said valve closed, means for moving said lever to open said valve and a second fluid tube adapted to direct fluid into said pocket to 95 maintain said valve open.

2. A device of the class described having in combination, a fluid tube, a valve adapted to control the passage of fluid through said tube, a fluid supply pipe, a discharge nozzle therefor, a lever operatively connected with said valve and provided with a pocket, the weight of said valve being normally adapted to maintain said pocket out of the range of the fluid discharged from 100 said nozzle and means for moving said lever to open said valve and place said pocket within the range of said nozzle.

3. A device of the class described having in combination, a fluid discharge tube, a valve adapted to control the discharge of fluid through said discharge tube, a fluid supply pipe, a discharge nozzle therefor, a lever operatively connected with said valve and provided with a pocket, the weight of 110 said valve being normally adapted to maintain said pocket out of the range of the fluid discharged from said nozzle, means for moving said lever to open said valve and place said pocket in the range of said 105 nozzle and means for automatically moving said valve to its inoperative position.

4. A device of the class described having in combination, a fluid tube, a valve adapted to control the passage of fluid through said tube, a fluid supply pipe, a discharge nozzle therefor, a lever operatively connected with said valve and provided with a pocket, the weight of said valve being normally adapted 125 to maintain said pocket out of the range of 130

the fluid discharged from said nozzle and an auxiliary fluid supply pipe adapted to discharge fluid into said pocket when said lever is in its normal position, whereby said lever may be operated to open said valve.

5. A device of the class described having in combination, a fluid tube, a valve adapted to control the passage of fluid through said tube, a fluid supply pipe, a discharge nozzle therefor, a lever operatively connected with said valve and provided with a pocket, the weight of said valve being normally adapted to maintain said pocket out of the range of the fluid discharged from said nozzle, an 10 auxiliary fluid supply pipe adapted to direct a jet of fluid into said pocket when said lever is in its normal position and means for regulating the passage of fluid through said auxiliary pipe.
- 15 20 6. A device of the class described having

in combination, a fluid tube, a valve adapted to control the passage of fluid through said tube, a fluid supply pipe, a discharge nozzle therefor, a lever operatively connected with said valve and provided with a pocket, the 25 weight of said valve being normally adapted to maintain said pocket out of the range of the fluid discharged from said nozzle, a valve adapted to regulate the passage of fluid through said auxiliary pipe, and a 30 spring to yieldingly maintain said valve closed.

In testimony whereof I have hereunto set my hand in presence of two subscribing witnesses.

JAMES PERRY.
